WITNESSES,

John H. Hutchins.
John J. Hutchins.

Inventor,
Irving Barker.

UNITED STATES PATENT OFFICE.

IRVING BARKER, OF BRAIDWOOD, ILLINOIS.

SELF-LUBRICATING CAR-WHEEL.

SPECIFICATION forming part of Letters Patent No. 372,290, dated November 1, 1887

Application filed March 14, 1887. Serial No. 230,816. (No model.)

To all whom it may concern:

Be it known that I, IRVING BARKER, a citizen of the United States of America, residing at Braidwood, in the county of Will and State of Illinois, have invented certain new and useful Improvements in Self-Lubricating Car-Wheels, of which the following is a specification, reference being had therein to the accompanying drawings.

10 This invention relates to certain improvements in a self-lubricating car-wheel, which improvements are fully set forth and explained in the following specification and claims, reference being had to the accompanying drawings, and the letters and figures of reference thereon, making a part of this specification, in which—

Figure 1 is a side plan view of the wheel having its detachable cap removed. Fig. 2 is a central vertical cross sectional view of the wheel and its detachable cap, and showing an axle-stub properly journaled in the wheel. Fig. 3 is a similar view of the cap detached from the wheel, and drawn on a larger scale. 25 Fig. 4 is an outside face plan view of said cap. Fig. 5 is an inside plan view of said cap, and Fig. 6 is a side view of said cap.

Referring to said drawings, W represents a car-wheel the hub H of which is constructed 30 with an annular oil-chamber, C, surrounding its box, extending from about the center of the hub to its forward end and cast with the front of said oil-chamber open, and C' are equidistant longitudinal partitions in said oil-chamber, 35 extending from its rear wall to near the front end of the box, but not across said oil-chamber. D is a detachable cap for closing said annular chamber C, and forms its outer walls, and its hollow, together with said annular chamber C, forms a receptacle for a lubricant for the wheel. A is an axle-spindle secured 40 in the box of the wheel by means of a linch-pin in the ordinary manner. The outer wall, F, of said chamber C is flared outward, as shown in Fig. 2, and the cap D is provided 45 with an annular flange, R, which is tapered to correspond with the flared form of said chamber C, as shown in Fig. 3. P is a packing surrounding said flange R. Said cap is 50 secured to the wheel-hub by means of forcing

its flange R within the flared sides of said chamber C, with the packing P between the flange R and wall F of chamber C, as shown in Fig. 2, and the adhesion of the said parts secure the cap D to the wheel without other means of fastening, thus dispensing with the use of bolts or screws for that purpose. Said flange R is provided with a series of transverse recesses, C', as shown in Fig. 3, for the reception of the partitions C', so said cap may 60 be forced within said chamber to the proper distance. Said cap D is provided with an oil-hole, O, for feeding the oil-receptacle, which oil-hole is closed on its inner side by means of the valve P', held by the spring S, secured to 65 the inner side of flange R, as shown in Fig. 3. Said spring permits said valve to be pressed inward by the spout of an oil-can when it is desired to supply oil to the oil-receptacle, and close said oil-hole when the can-spout is removed. Said oil-hole O may be closed by means of a spring-stopper, T, as shown in dotted lines in Fig. 3, if desired. Said cap is also provided with lugs L L, as shown in Figs. 4 and 6, which lugs furnish means for removing 70 said cap by means of a lever.

The principal new feature in this invention consists in having the outer walls, F, of the chamber C flared outward, and the cap D having its flange R tapered to correspond with 80 the flared walls of said chamber, and securing the cap to the wheel-hub by means of forcing its flange within the flared wall of said chamber C, (a packing having first been placed between said flange and wall,) and thus hold the 85 cap in place simply by its adhesion with the chamber into which its flange is forced, and thus dispense entirely with the use of bolts or screws for that purpose.

Having thus described my invention, what 90 I claim as new, and desire to secure by Letters Patent, is as follows, to wit:

1. The self-lubricating car-wheel shown and described, having the oil-chamber C surrounding its box and cast with its front open, 95 and its outer wall, F, flared outward, said chamber having the equidistant longitudinal partitions C' extending from the rear wall to near the front end of said box, but not entirely across said chamber, in combination 100

with the cap D, having the flange R tapered to correspond with the flared wall of said chamber, and having an oil-hole, O, provided with means for opening and closing said oil-hole, 5 and the packing P, between said flange and wall, substantially as set forth.

2. The combination of the wheel W, having the chamber C, surrounding its box, and having its outer wall, F, flared outward, and the cap D, having its flange R tapered to corre-

spond with the flared wall of said chamber and adapted to close said chamber C by means of forcing said tapered flange within said flared chamber, substantially as and for the purpose set forth.

IRVING BARKER.
